UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

BRAKE FOR SEQUENCE-SWITCHES.

1,279,909.

Specification of Letters Patent. Patented Sept. 24, 1918.

Application filed September 11, 1916. Serial No. 119,488.

To all whom it may concern:

Be it known that I, JOHN NEWBERRY REYNOLDS, a citizen of the United States, residing at Greenwich, in the county of Fairfield and State of Connecticut, have invented 5 certain new and useful Improvements in Brakes for Sequence-Switches, of which the following is a full, clear, concise, and exact description.

10 This invention relates to a switch structure commonly called a sequence switch, in which there is a rotatable contact carrying member, and particularly to means for preventing overrun of the rotatable member.

15 Devices of this character formerly employed consist of a metallic disk attached to the rotatable member and having a fluted edge with which a roller coöperates and is held in forcible engagement therewith by a spring arm. A braking action is produced 20 as the roller engages the fluted edge of the disk. It is obvious that the retarding force produced by this arrangement is very unsteady.

25 The object of this invention is the provision of means for applying a steady retarding force to the rotating member. In the present embodiment of the invention, this is effected by means of a metallic disk 30 attached to the rotatable member revolving between two friction pads.

35 The advantages of this device over those formerly employed are that the torsional vibrations in the rotatable member, due to the varying power required for driving the member as the roller rides over the fluted edge, are eliminated; that by regulating the pressure of the pads on the metallic disk, the switch can be made to stop instantly 40 when the driving source of the member is disengaged therefrom, and that less power is required to drive the shaft.

45 For an illustration of the brake and of its operation, reference is made to the accompanying drawings: Figure 1 is a side elevation of a sequence switch employing this brake. Fig. 2 is a sectional view taken on the line 2—2. The sequence switch shown, except as to the retarding means, 50 is similar in structure to that described in Patent 1,127,808, patented February 9, 1915. This switch is used merely to show a switch employing this brake, and it is to be understood that the invention is not limited to the 55 application of the brake to this particular

switch, as it is obvious that in applying this brake to other switch structures, many changes may be made in the structure without departing from the spirit of the invention.

60

Referring now to the drawing, in which the same reference characters are applied to the same parts in the various figures, 1 represents a frame having the extended portions 2 and 3. Rotatably mounted between the portions 2 and 3 is the shaft 4. Non-rotatably mounted on the shaft 4 is a plurality of disks 31, having contacts 32 and 32' thereon which are adapted to control various circuits (not shown). Fixed to one end of the shaft is a disk 30 having a plurality of radially extending arms 7 of flexible material. The disk 9 is secured to the outer ends of the arms 7 and is adapted to be attracted against the resiliency of these supporting arms 7 when magnet 12 is energized. Disk 9, when attracted, is brought into forcible engagement with the friction disk 10, which is attached to the rotating power shaft 11, thereby rotating 70 shaft 4.

75 Also fixed to shaft 4 is a disk 22 of fiber or other insulating material. On each side of the insulating disk there is secured a metallic disk or plate. One of these disks, 13, 80 is of larger diameter than that of the insulating disk, and rotates between two friction pads 14 and 14', which may be of any suitable frictional material such as cork. Friction pads 14 and 14' are held in forcible engagement with the disk 13 by spring arms 15 and 15' respectively, which are secured to an extension 24 of the frame 1 by set screws 23. A slot 17 is cut out of each of the spring arms, and the clamping screw 16 fits therein 85 and clamps the two springs together. The spring arms diverge from their fastened end so that as the clamping screw 16 is moved in the slot away from their fastened end, the pressure exerted on disk 13 by the friction contacts 14 and 14' is increased. Thus, the retarding force can be varied any desired amount simply by changing the position of this clamping screw.

95 When the shaft 4 rotates, disk 13 revolves 100 between the pads 14 and 14', producing friction which tends to stop the shaft from rotating, and when disks 9 and 10 are disengaged, this friction stops further rotation of the shaft.

110

Secured to the other side of the insulating disk 22 is the metallic disk 20. This metallic disk has a series of notches 18 around its edge. Brushes 19 and 21 are arranged to coöperate respectively with the notches 18 and the imperforate portion 20 of the disk 18. This construction may be used to control the local circuit for the magnet 12 to determine the stopping positions of the switch.
10 The function of this arrangement is to assure a complete passage of the switch from one stopping position to the next.

What is claimed is:

1. In a switch, the combination with a frame, a rotatable shaft, and means for rotating said shaft, of a controlling device for said shaft comprising a disk secured to said shaft, two flat springs, means engaging one end of said spring for clamping said springs together, means for fastening said clamped portion of said springs to said frame, friction pads secured to the other end of each spring and in engagement with said disk, and a screw extending through slots one in each spring, arranged to vary the pressure exerted by said friction pads against said disk.
2. In a switch, the combination with a frame, a rotatable shaft, and means for rotating said shaft, of a controlling device for said shaft comprising a disk secured to said

shaft, two flat springs, each spring having a slot extending lengthwise thereof, means engaging one end of each spring for clamping said springs together, means for fastening said clamped portion of said springs to said frame, friction pads secured to the other end of each spring and in engagement with said disk, and means extending through the slots of both springs and slidably therein to vary the pressure exerted by said friction pads against said disk.

3. In a switch, the combination with a frame, a rotatable shaft, and means for rotating said shaft, of a controlling device for said shaft comprising a disk secured to said shaft, two flat springs, each spring having a slot extending lengthwise thereof, means engaging one end of each spring for clamping said springs together, means for fastening said clamped portion of said springs to said frame, friction pads secured to the other end of each spring and in engagement with opposite sides of said disk, and a clamping screw extending through the slots of both springs and slidably therein to vary the pressure exerted by said friction pads against said disk.

In witness whereof, I hereunto subscribe my name this 8th day of September, A. D. 60
1916.

JOHN NEWBERRY REYNOLDS.
